UNITED STATES PATENT OFFICE.

PIERRE I. CHANDEYSSON, OF ST. LOUIS, MISSOURI, ASSIGNOR TO MARSHALL ELECTRIC COMPANY, OF CHICAGO, ILLINOIS, A CORPORATION OF ILLINOIS.

CARBON-PILE SUPPORT.

Application filed October 13, 1922. Serial No. 594,387.

To all whom it may concern:

Be it known that I, PIERRE I. CHANDEYSSON, citizen of the United States, residing at St. Louis, in the county of St. Louis and 5 State of Missouri, have invented certain new and useful Improvements in a Carbon-Pile Support; and I do hereby declare the following to be a full, clear, and exact description of the invention, such as will enable others 10 skilled in the art to which it appertains to make and use the same.

My invention relates to the class of rheostats in which the resistance is varied by changing the compression of a resistance material, such as a pile of carbon disks. Viewed in some of its general aspects, my invention aims to provide means for eliminating the interference of friction with the 15 sensitiveness and uniformity of response of the resistance material to changes in compression, for preventing a tilting or canting of portions of the resistance such as would interfere with the proper response in resistance to variations in pressure, and for affording an arrangement of parts in which the 20 variations in resistance will be closely proportioned to the variations in pressure. Furthermore, my invention aims to provide a rheostat of this general class which will 25 be simple and inexpensive in construction, which can readily be adjusted as to the range of resistance afforded by the same, which will permit a wide range of resistance to be secured in response to a small amount 30 of change-actuating energy, and which will lend itself equally well to embodiments in which the actuating energy is to effect either an increase or a decrease of the resistance.

While compressible resistances of the general type of carbon piles have long been employed, such carbon piles have commonly been objectionable both because of the variations in resistance due to friction between the disks of the pile and to friction between 40 the disks and their inclosing tube, and because of the irregular variations in resistance due to a relative tilting or canting of the disks constituting the pile. For example, such carbon piles have commonly been mounted 45 on a rigid support and the variation in pressure has commonly been exerted in such a way as to tend to rotate, tilt or otherwise shift the relative position of the carbon disks comprising the pile, thereby introducing 50 both a waste of energy in the mechanism 55

employed for varying the compression and an uncertainty as to the effective resistance secured with any particular position of this mechanism. Both this waste of energy and the uncertainty as to the resulting resistance 60 have been further increased by the friction of the disks against the tube inclosing the same and by the friction in the mechanism employed for varying the compression. Consequently, rheostats of this class have 65 been limited as to the purposes for which they could be commercially employed and have been barred from many fields for which a carbon pile should form an ideal resistance.

Moreover, the mechanisms commonly employed for varying the compression of a compressible resistance have disregarded the fact that the change in resistance does not vary uniformly with pressure but varies 70 according to a hyperbolic function of the 75 pressure. Consequently, where the movement of the actuating member is substantially in proportion to the actuating effort, as in the case of a solenoid core moved by the flow of current through the solenoid, the 80 resulting change in pressure did not respond with any uniformity to the changes in the actuating effort, and mechanism employing cams or the like for correcting this 85 discrepancy has introduced such complications and such friction as to be commercially prohibitive for many purposes.

My present invention aims to overcome all of the above named objections to rheostats of the compressible resistance type and 90 aims to do so by employing an exceedingly simple and durable arrangement of parts. For this purpose, my invention aims to provide a construction in which the carbon pile is movable as a unit and is not supported by 95 the tube or other guide which maintains the carbon disks in alinement, and one in which the pressure is applied to the carbon pile axially of the latter so as to prevent any relative movement of the constituent disks, 100 thereby eliminating the heretofore objectionable friction and uncertainty of the resulting resistance. It also aims to provide an arrangement in which the pressure applied to the carbon pile will be a hyperbolic 105 function of the movement of the actuating member, so that by suitably proportioning the various parts I can make this hyperbolic relation correspond to the above mentioned 110 relation between the variations of pressure

and resistance in a carbon pile and hence can make the resulting resistance uniformly responsive to the movement of the actuating member. Furthermore, my invention aims to accomplish this last named purpose by providing an exceedingly simple construction employing three relatively movable members interconnected in the form of a triangle with pivotal movement about each apex of the triangle and with the carbon pile or other compressible resistance forming one side of the triangle. It also aims to provide a construction which will readily permit of adjusting the general range of variation of the resistance and which will readily be adapted for purposes where the effective resistance is to be either increased or decreased in response to variations in the flow of current through an electromagnet. Still further and also more detailed objects will appear from the following specification and from the accompanying drawings, in which

Fig. 1 is a somewhat diagrammatic view of an electrically controlled rheostat embodying my invention and arranged for having the resistance decreased in response to an increase of current through an electromagnet.

Fig. 2 is a similar view showing an embodiment in which the pressure is increased in response to the flow of current through an electro-magnet.

Fig. 3 is a similar view showing an embodiment arranged after the general principle of Fig. 1 and including adjustable means for varying the range of compression of the resistance.

Fig. 4 is a somewhat diagrammatic view of another embodiment in which the resistance is decreased in response to an increase of current flowing through an electro-magnet, namely one in which the longer member of the triangular system is stationary and in which the actuating effort is imparted to one of the shorter sides of the triangle.

Fig. 5 is a diagrammatic view of the triangular system forming the basis of operation of Fig. 1.

Fig. 6 is a similar diagram showing the system employed in Fig. 4.

Fig. 7 is a perspective view of an electrically controlled rheostat embodying my invention and employing the underlying principle of Figs. 1 and 5.

Fig. 8 is a central and longitudinal section through the resistance member of Fig. 7.

Fig. 9 is a front elevation of the electricaly controlled rheostat of Fig. 7 with some of the parts in section, showing the movable portions shown in full lines in the maximum compressing position and with dotted lines showing a position in which the electro-

magnet has effected a considerable releasing of the compression.

Referring first to the more diagrammatic views, Fig. 1 shows a supporting member 1 equipped with a conical or knife-edge projection 2 which is socketed in a corresponding recess formation in one of the end plates 3 of a compressible resistance comprising a pile of carbon disks 4 slidably inserted in an insulating tube 5, the carbon disks being insulated from the pressure applying heads 3 by insulating disks 6. The end piece or pressure-transmitting head 3^a at the other end of this resistance member also has a corresponding recess formation entered by a suitably pointed projection 7 on a swinging arm 8 which forms the actuating member of the appliance. This member 8 carries another projection 9 entering a recess formation in the support 1 out of alinement with the axis of the resistance member. Thus arranged, the rigid portion of the support disposed between the tips of the projections 2 and 9 corresponds to the thrust arm T of the diagram of Fig. 5, while the compressible resistance corresponds to the arm R of that figure and the actuating member corresponds to the arm 8 of the latter figure. This actuating arm is longer than either of the two other arms and the arms T and R form an oblique angle with each other. By making this angle a fair approach to 180° and assuming the thrust member T to be stationary, it will be evident that a pivotal movement of the arm 8 about the apex 9 of the triangulated mechanism will compress the resistance member R.

Consequently, in the embodiment of Fig. 1, gravity will have this compressing effect, while the lifting action of an electromagnetic coil 10 on an arm core 11 carried by the actuating arm 8 will swing the arm 8 in the direction of the arrow 12 of Fig. 5, thereby releasing the compression and correspondingly changing the resistance. Furthermore, since the variation in compression of the member R in a system of three pivotally interconnected members arranged after the manner of Fig. 5 is a hyperbolic function of the extent of pivotal movement of the arm 8 about the pivot apex 9, I secure a change in compression corresponding in general relationship to that which exists between the amount of compression in a carbon pile and the resulting resistance. By suitably proportioning the various parts of the system of Fig. 5 I can therefore cause the change in resistance to be approximately uniformly proportioned to the extent of movement of the actuating member, which is highly desirable.

However, the mechanism of Fig. 1 can readily be inverted effectively after the manner of Fig. 2, so as to have the compression relaxed by the effect of gravity on the ac-

tuating arm, while the lifting effect of the electro-magnet swings the actuating arm so as to increase the compression, the principle employed then by an inversion of that of Fig. 5.

In practice, I desirably also provide means for initially adjusting the compression of the resistance member, thereby predetermining the general range of resistance afforded by my mechanism. Thus, Fig. 3 shows a somewhat diagrammatic view corresponding in operating principle to that of Fig. 1 but having the thrust tip 7 on one end of the actuating arm formed upon a screw 13 which is adjustable with respect to the arm 8. Furthermore, while I have heretofore pictured and described embodiments of my invention in which the relatively short thrust arm T of the system is stationary and in which the actuating effort is applied to the longer arm 8, I do not wish to be limited as to any such features of construction or arrangement. For example, Fig. 4 shows an embodiment in which the long arm 14 is stationary and forms the support for the other arms, and in which the magnet coil 10 is arranged for moving a core 11 mounted on a movable thrust member 15, the resistance member in this case being disposed between this movable thrust member and an adjusting screw 13 threaded upon the longer stationary member 14. In this case, the system of forces is more after the manner of Fig. 6, it being obvious that the general principle of my invention can be employed in any arrangement which tends to bring the members T and R of the system more nearly into alinement with the longer arm, or which varies the distance between the longer arm 40 and the pivotal juncture of the arms R and T.

As a practical exemplification of my invention, Figs. 7 and 9 show an electrically controlled rheostat in which a back plate 15 serves as the support for the appliance as a whole. This plate has a pair of webs 16 between which a magnet coil or spool 17 is secured by screws 18, the lower web 16 being perforated to clear an iron core 19 which extends part way up into the coil and which is carried by one end of the actuating arms 20 of the rheostat. The other end of the arm 20 has a recess facing the magnet coil and affording a pivotal bearing for the outer end 55 of a thrust member 21, this thrust member being a pin which extends through a lug 22 on the back plate and which is secured to this lug by a screw 23. Adjacent to the magnet coil the actuating arm 20 carries a rigid riser 25 through which an adjusting screw 13 is threaded. This screw is normally locked against movement by locknuts 26 and has a pointed tip extending toward the pointed tip 24 of the thrust member 21.

Interposed between the said two pointed

tips is the resistance member of the appliance, consisting of a pile of carbon disks 4 operatively interposed between two end disks or pressure applying members 3, each of the latter having an outwardly directed recess formation disposed axial of the pile of disks and entered by one of the said pointed tips. The carbon disks are insulated from the end disks 3 by interposed insulating disks 6, all of the said elements 4, 6 and 3 being retained in operative alinement by suitable guide means such as an insulating tube 5 slidably housing the same.

With the parts thus arranged, it will be obvious that gravity tends to swing the right hand or free end of the actuating arm downwards, thereby tending to bring the axis of the resistance more nearly into alinement with the effective axis of the thrust member, the latter axis being that shown in dotted lines in Fig. 9. With the actuating arm constructed as a rigid member, any such downward movement of the actuating arm will decrease the effective length of the resistance member, thereby compressing the carbon pile. However, any raising of the actuating arm against the action of gravity by the attraction of the magnetic coil 17 on the core 19 will tend to increase the distance between the said pointed tips and hence will relax the compression. By adjusting the position of the screw 13 with respect to the lug 25 I can readily adjust the initial compression of the resistance, while by varying the diameter and quality of the carbon disks 100 I can readily vary the carrying capacity and can secure further changes in the general range of the obtainable resistance. So also, by substituting magnet spools of different windings I can readily change the responsiveness of the rheostat to various electrical conditions, thereby permitting the same metal parts to be employed in apparatus suitable for a wide variety of conditions.

To prevent the action of gravity from swinging the actuating arm too far when there is no current flowing through the magnet coil, I desirably provide a stop pin 26 secured to the supporting back 15 and underhanging the actuating member. However, I do not wish to be limited to this or other features of the above described embodiments of my invention, it being obvious that both the construction and arrangement might be varied in many ways without departing either from the spirit of my invention or from the appended claims.

I claim as my invention:—

1. A rheostat comprising in triangular formation a rigid long arm, a shorter thrust arm, and a compressible resistance arm, the thrust arm and the resistance arm being pivoted at one end to each other and at their free ends to the said long arm; the long arm extending at acute angles to both of the

other arms; and means for relatively moving the said arms while maintaining their said pivotally connected disposition so as to vary the size of the said acute angles and the effective length of the compressible resistance arm.

2. A rheostat comprising in substantially triangular formation a stationary thrust arm, a resistance arm pivoted at one end to one end of the thrust arm and extending in oblique continuation of the thrust arm, and a third arm longer than the resistance arm, the third arm being rigid and directly pivoted at its ends respectively to the other ends of the thrust arm and of the resistance arm, the resistance arm having as a part thereof a resistance adapted to be compressed when the third arm is moved about its pivotal connection to the thrust arm toward the pivotal connection between the thrust arm and the resistance arm so as to vary the obliqueness of the thrust arm with respect to the resistance arm.

3. A rheostat as per claim 2, in combination with electromagnetic means for relatively moving the third arm with respect to the thrust arm.

4. A rheostat as per claim 2, in which the three arms are so disposed that gravity will tend to move the longer arm in one direction with respect to the thrust arm, in combination with electromagnetic means for moving the longer arm in the opposite direction with respect to the thrust arm.

5. A rheostat comprising a pair of rigidly spaced pivots, in combination with a rigid arm and a compressible resistance pivotally connected to each other and respectively fulcrumed upon the said pivots, the resistance being entirely supported through its pivotal connections to the said arm and to the pivot upon which the resistance is fulcrumed.

6. The combination with a compressible resistance medium whose rate of resistance variation is substantially a hyperbolic function of the compressing pressure applied to the resistance medium, of thrust means engaging one end of the resistance medium to resist a bodily movement of the said medium, a compressing member movably mounted with respect to the thrust means, and actuating means operatively connected to the compressing member for moving the latter at a rate which is also a hyperbolic function of the compressing pressure applied to the resistance through the compressing member by the movement of the latter.

7. In combination, a compressible resistance, thrust means pivotally connected to the resistance at one end, and a lever pivotally connected to the other end of the resistance and cooperating with the thrust means in affording the entire support for the resistance.

8. The combination with guide means of

an assemblage of disks freely slideable with respect thereto, the said assemblage including metal end disks, compressible resistance disks disposed between the end disks, and insulating elements respectively insulating the end disks from the resistance disks; and compressing means engaging the endward faces of the end disks to clamp the said assemblage of disks, the said compressing means forming the sole support for the assemblage of disks and the guide means.

9. A resistance member including a carbon pile, a thrust member having one end thereof in pivotal engagement with one end of the resistance member, a relatively longer member having two portions thereof respectively in engagement with the other ends of the thrust member and the resistance member, the last named two members extending in continuation of each other and at a relatively large angle to each other, the resistance member being supported solely by the said other two members.

10. A rheostat comprising a pair of rigidly spaced pivots, and a pair of pivotally joined arms fulcrumed at their free ends respectively upon the said pivots, the said arms extending at an acute angle to each other, one of the said arms having a compressible resistance constituting the main portion thereof, a solenoid core fast upon one of the said arms, and a magnetizing coil associated with the core to move the latter so as to vary the said angle.

11. In combination with a compressible resistance, means having a part pivotally engaging an end of the resistance, and rigid means having a part movably engaging the opposite end of the resistance and having a second part movably engaging the first named means at a point to one side of the axis of the resistance whereby upon relative movement between the resistance and rigid means in one direction the resistance will be compressed and upon movement in a second direction the compression will be relaxed, the resistance being entirely supported by its engagement with the said parts.

12. A rheostat comprising a pair of rigidly spaced pivots, in combination with a rigid arm and a compressible resistance pivotally connected to each other and respectively fulcrumed upon the said pivots, the resistance being entirely supported through its pivotal connections to the said arms and to the pivot upon which the resistance is fulcrumed, and means associated with the resistance for varying the effective length thereof so as to adjust the initial compression of the resistance.

13. The combination with a carbon pile, of a pair of heads between which the pile is interposed, and two rigid thrust members respectively engaging the said heads, each thrust member having substantially a point

engagement with the adjacent heads, one of the thrust members extending in oblique extension of the axis of the carbon pile, the other thrust member extending at an acute angle to the said axis past both the carbon pile and the aforesaid thrust member and being pivoted to the outer end of the latter, the carbon pile being supported solely by the said engagement thereof with the thrust members.

14. The combination of a resistor whose

conductivity is variable by compression, of compression-varying means engaging the same and forming the sole support for the resistor, the supporting and compressing engagement between the said means and the resistor being confined to a point or knife-edge bearing at each end of the resistor.

Signed at St. Louis, Missouri, October 10th, 1922.

PIERRE I. CHANDEYSSON.
